UNITED STATES PATENT OFFICE

97,508

DESIGN FOR A SLEEVE HOLDER

August Schultz, New York, N. Y.

Application September 25, 1935, Serial No. 58,697

Term of patent 3½ years

To all whom it may concern:

Be it known that I, August Schultz, a citizen of the United States, residing at New York city, in the county of New York and State of New York, have invented a new, original, and ornamental Design for a Sleeve Holder, of which the following is a specification, reference being had to the accompanying drawing, forming a part thereof.

Fig. 1 is a plan view of a sleeve holder, showing my new design.

Fig. 2 is a front elevational view of Fig. 1.

Fig. 3 is a side view of Fig. 1.

I claim:

The ornamental design for a sleeve holder, as shown.

In testimony whereof I have affixed my signature.

AUGUST SCHULTZ.
